UNITED STATES PATENT OFFICE.

JAMES T. STODDARD, OF PORTLAND, OREGON.

SAW-SHIFTER FOR GANG-EDGERS.

967,994.

Specification of Letters Patent. Patented Aug. 23, 1910.

Application filed November 24, 1909. Serial No. 529,756.

To all whom it may concern:

Be it known that I, JAMES T. STODDARD, a citizen of the United States, residing at Portland, in the county of Multnomah and 5 State of Oregon, have invented a new and useful Improvement in Saw-Shifters for Gang-Edgers, of which the following is a specification, reference being had to the accompanying drawings.

10 My invention relates to the class of gang-edgers used in saw-mills to cut saw-logs into boards of various widths and thicknesses.

15 The object of my invention is to provide a device in which each saw shifter moves its own gage and is automatically locked in and released from position by means of power clutching mechanism. I attain these objects as well as other advantages, by the construction, combination and arrangement of parts 20 illustrated in the accompanying drawings, which form a part hereof.

Figure 1 is a front elevation of a gang-edger showing my device therein. Fig. 2 is a side elevation of said edger. Fig. 3 is an 25 enlarged sectional view of a portion of the machine on the line E—E of Fig. 1 with portions of the shifter broken away to illustrate the mechanism within.

Like numerals and letters refer to like 30 parts throughout the views.

A is the standard frame of the edger.

B is the saw arbor suitably mounted in the frame and carrying a battery of saws, keyed on the arbor in the ordinary way.

35 C and D are feed rollers mounted in the frame A in suitable position.

In the front part of the frame A are transverse shifter rods, the ends of which pass through openings in the respective sides 40 6—6' of the frame in sliding engagement therewith. Saw-shifting bars 7 are rigidly secured in suitable position upon the shifting rods 5 at right angles thereto. The shifting bars 7 are provided with yokes 8 in

45 the usual manner of like machines and these extend far enough longitudinally of the machine to engage the sides of the saws 4. The shifters are provided with integral handles 9. A scale plate 10 is rigidly secured to the 50 sides 6—6' in front of the edger and transversely thereto. This scale plate is inclined at a suitable angle toward the rear of the edger. It need only be graduated for a suitable distance from its left end. Beginning

with the shifter bar to the left and in order 55 toward the right the shifter bars are respectively provided with scale plates 11, 12, 13 and 14 inclined at the same angle as the rigid plate 10 and rigidly secured at the left end of each to its respective shifter near the 60 handle thereof. These scale plates are movable with the shifters and are held in alignment on their free ends by engagement with a pointer hook 15 extending over them, or they may be otherwise guided by sliding in 65 a groove or an opening in the side 6' of the frame A. Each scale plate just clears the upper surface of the scale plate of the shifter next to the left of the one to which it is secured, the one on the extreme left clearing the rigid scale plate 10 in the same 70 manner.

The shifter bar scale plates are arranged, the first to move laterally in front of the face of the rigid plate 10 and each succeeding movable scale plate to move laterally in front of the face of the scale plate of the next shifter bar to the left. The scale plates are so arranged and graduated with relation to the longitudinal direction of the saws 80 and shifters that the necessary allowance for saw-kerf is pre-determined when the shifters are moved laterally to set the saws to cut material. When so moved and locked with the power clutch herein described, the 85 saws are placed and firmly held accurately in position to saw material of the desired dimension, as it is read upon the scale plates. A hook pointer 15 is rigidly secured at the right end of the scale plate 10 and extended 90 over it and downward in engagement with the face of the outer scale plate 14. By means of this the distance between the nearest saw and the pointer may be read to ascertain the amount of material within that 95 space.

In the front part of the edger and immediately over the shifters toward the rear end thereof a rigid bar 16 extends transversely of the edger, being secured at its 100 ends to the respective sides 6—6' of the frame. The bar 16 engages a semi-circular groove 17 Fig. 3, immediately over it in the frame A, which groove may if desired be faced with Babbitt metal or other suitable material. On the lower side of each shifter a clutch lever 18 is pivoted on its rear end to the shifter by a pin 19. The levers 18

are formed with a suitable contact surface 20 on the upper sides to engage the lower surface of the rigid bar 16. An adjusting screw 21 Fig. 3, may be also provided in the clutch lever 18 extending vertically upward, and which may be brought into engagement with the lower surface of the bar 16. The rear end of the lever 18 extends horizontally into a vertical cylinder 22 which is secured 5 to the lower side of the shifter and wherein the lever 18 is secured upon a vertical piston rod 23. An expansion coil spring 24 mounted upon the upper end of the piston rod 23 engages the lower surface of the top of the cylinder and also the upper surface of the rear end of the lever 18. The lower end 10 of the cylinder 22 has an opening 25 which is the means of receiving and transmitting power fluid from a power generating source into the cylinder, below a piston 26 and through a valve port 27. The power fluid may be transmitted through a hose pipe connected with the lower end of the duct 25. The piston 26 is secured to the lower end 15 of the piston rod 23. The cylinder is also provided with an exhaust port 28 and a valve port 29 therefor. A valve 30 is arranged transversely of the cylinder. It extends through the lower end of the cylinder 20 and commands the ports 25 and 28. Its rear end is pivoted to the lower end of a bell crank latch lever 31 which is pivoted at its angle on a pivot 32 in the lower side of the shifter handle. An expansion coil spring 33 is mounted on the rear end of the valve 25 stem, engaging the cylinder with its forward end and a transverse pin 34 in the valve stem with its other end.

It will now be seen that while the valve 40 27 is open as in Fig. 3 the power fluid forces the piston 26 upward and it in turn causes the end of the lever 18 to rise and the lever to engage the rod 16 and force it against the groove 17, the friction pressure on which retains the shifter in a fixed position with 45 relation to the sides of the edger frame. Upon grasping the lever latch 31, raising it and holding it thus, the fluid power pressure is released in the cylinder through the port 28 and the spring 24 depresses the lever 18, releasing its friction clutch on the rod 16. The shifter may then be slid laterally 50 between the sides of the frame and the saw moved by it to any position desired, as predetermined by the gages on the scale plates. When in position, by releasing the lever latch 31 the valve 30 is moved forward by 55 the spring 33 and the power fluid again admitted to the cylinder, causing the piston 26 to rise and bring the lever 18 again into friction clutch with the rod 16 as shown in Fig. 3.

The shifter at the extreme left is first set by the graduated scale plate 10, the next one 60 is set by the scale plate 11 on this shifter and

each succeeding one in the same manner. By means of the pointer 15 at the right, the distance between it and the nearest saw may be read and the width of the material remaining on the right can be calculated, for 70 the purpose of moving the saw to cut the same as may be desired. The shifter scale plates being thus graduated and arranged, full allowance is made for the loss of board measurement caused by the saw-kerf and 75 this enables the operator to set the saws for any full measurement of boards as indicated on the scale plates, without the necessity for mentally calculating the loss for saw-kerf and allowing for it upon the scale as he 80 shifts the saws. Far greater accuracy and speed is thereby attained in the operation of the machine. The adjusting screw 21 may be used or omitted as desired. It may be of use in retaining the clutch surface against 85 the bar 16 when the contact surfaces become worn.

The arrangement of scale plates on the shifters and the pointer 15 are improvements upon the device shown in my former 90 Patent No. 879,923 dated February 25, 1908, but are included in my Canadian Patent No. 117,308, dated March 16, 1909. The friction clutch now shown is an improvement upon the edger shown in both of said patents. It 95 is also to be noted that my device might be arranged in a reverse manner, that is to say, the spring 24 may be placed below the lever 18 to retain it in friction clutch on the rod 16, and the cylinder be above the lever 100 so that power would be applied to release the clutch instead of to retain it as illustrated. Such an arrangement I contend to be an equivalent of the one herein described. It may also be noted that the scale plates 105 might be arranged reversely on the shifters and such arrangement I likewise contend to be an equivalent of that illustrated.

Having thus particularly described my invention as aforesaid I claim:

1. A gang-edger saw-shifter provided with clutching or locking mechanism comprising a cylinder 22 secured to the shifter, a piston 23 therein, a cylinder port 25 to receive and transmit pressure power fluid from a convenient power source, a cylinder exhaust port 28, a cylinder valve 30 commanding the ports, means to open and close the valve, means to retain the piston at the end of its inward stroke, a clutch lever 18 secured at one end to the piston rod 23, its opposite end pivoted upon the shifter, the lever being formed with a suitable contact surface to engage an oppositely disposed friction bar 16, substantially as described. 115 120 125

2. In a gang-edger the combination with a rigid friction bar 16 in a frame A of the edger, of saw-shifter clutching or locking mechanism comprising a cylinder 22 secured to the shifter, a piston 23 therein, a cylinder 130

port 25 to receive and transmit pressure power fluid from a convenient power source, a cylinder exhaust port 28, a cylinder valve 30 commanding the ports, means to open 5 and close the valve, means to retain the piston at the end of its inward stroke, a clutch lever 18 secured at one end to the piston rod 23, its opposite end pivoted upon the

shifter, the lever being formed with a suitable contact surface to engage the oppositely disposed friction bar 16, substantially as described.

JAMES T. STODDARD.
